DESIGN FOR A VERTICAL BUMPER

William E. Porter, Lowell, Mass., assignor to A. S. Campbell Co., Inc., East Boston, Mass., a corporation of Massachusetts

Application June 19, 1937, Serial No. 69,926

Term of patent 7 years

To all whom it may concern:

Be it known that I, William E. Porter, a citizen of the United States, residing at Lowell, county of Middlesex, and State of Massachusetts, have invented a new, original, and ornamental Design for a Vertical Bumper, of which the following is a specification, reference being had to the accompanying drawing, forming part thereof.

In the drawing:—

Fig. 1 is a front elevation of a vertical bumper showing my new design;

Fig. 2 is a side elevation; and

Fig. 3 is an enlarged section on line 3—3 of Fig. 1.

I claim:—

The ornamental design for a vertical bumper, substantially as shown.

WILLIAM E. PORTER,
